EX
12,011

Design No. 12,011, dated November 2, 1880.

UNITED STATES PATENT OFFICE.

EDUARD LEISSNER, OF NEW YORK, N. Y., ASSIGNOR TO LEISSNER & LOUIS,
OF SAME PLACE.

DESIGN FOR WALL-PAPER.

SPECIFICATION forming part of Design No. 12,011, dated November 2, 1880.

Application filed July 31, 1880. Term of patent 3½ years.

To all whom it may concern:

Be it known that I, EDUARD LEISSNER, of New York, in the county and State of New York, have invented a new and original Design for Wall-Paper, of which the following is a specification.

This invention relates to a new and original design for wall-paper and similar fabrics; and it consists in the novel grouping and configuration of figures hereinafter more fully described.

The accompanying photograph illustrates a face-view of wall-paper having my new design.

15 The figure A A A is composed of a zigzag or step-like stripe, presenting the appearance of a series of steeply-inclined steps or stairs running up and down and leaving alternate upper and lower openings, in which openings appear the bell-shaped flowers or ornaments B B B. The flowers B, which occupy the upper openings between the steps A, contain in their open cups the circular half-rosettes C. These flowers B, which occupy the lower openings, form a group consisting of the flower B, a circular half-rosette, C, in the cup thereof, a small cup-like flower, a, projecting from the half-rosette C, and the two bell-shaped flowers e e, one on each side of the flower B. A vine, 20 D D, with cup-like flowers d d upon it, intertwines with the figure A and joins the edges of the figures B B B. Stripes E E, containing a rectangular pattern running between two

parallel bars, serve to divide the designs when repeated to form the wall-paper. These stripes 35 are partly covered at intervals by the bell-shaped flowers d e.

The effect of my novel design as a whole is that of a series of steep steps with a vine upon them, running up and down between two parallel ornamented stripes, and having the upper and lower interstices between the steps occupied by bell-shaped flowers and their ornamentation.

I claim—

1. The design for wall-paper, consisting of the step-like zigzag figure A, vines D, and flowers d, substantially as shown.
2. The design for wall-paper, consisting of the figure B and half-rosette C, substantially 50 as shown.
3. The design for wall-paper, consisting of the group composed of the figure B, half-rosette C, and projecting figure a, substantially as shown.
4. The design for wall-paper, consisting of the figure E, with its rectangular ornamentation, and the bell-shaped flowers d e, substantially as shown.
5. The design for wall-paper, consisting of 60 the figures A B C D E a e d, substantially as shown.

EDUARD LEISSNER.
